UNITED STATES PATENT OFFICE.

JAMES S. DONOHUE, OF PHILADELPHIA, PENNSYLVANIA.

DESIGN FOR A LAMP-WICK.

SPECIFICATION forming part of Design No. 24,437, dated June 25, 18. 5.

Application filed February 13, 1895. Serial No. 538,300. Term of patent 7 years.

To all whom it may concern:

Be it known that I, JAMES S. DONOHUE, a citizen of the United States, residing at Philadelphia, in the county of Philadelphia and State of Pennsylvania, have invented and produced a new and original Design for Lamp-Wicks, of which the following is a specification, reference being had to the accompanying drawings, showing a part thereof.

10 The design is particularly adapted for the ornamentation of lamp wicks.

Figure 1 is a view in elevation of the front surface of the wick. Fig. 2 is a similar view of the rear surface, and Fig. 3 is a view in 15 perspective showing a portion of opposite surfaces.

The leading feature of the design consists in the arrangement of parallel strips of contrasting shades on the obverse surface and oblique lines of contrasting shades on the reverse 20 surface.

Having thus fully described my design, what I claim is—

25 The design for a lamp wick herein shown and described.

In testimony whereof I have hereunto affixed my signature in presence of two subscribing witnesses.

JAMES S. DONOHUE.
